UNITED STATES PATENT OFFICE.

HAYWARD A. HARVEY, OF ORANGE, NEW JERSEY.

IMPROVEMENT IN MODES OF FORMING THE NICKED HEADS OF SCREWS.

Specification forming part of Letters Patent No. **154,865**, dated September 8, 1874; application filed March 6, 1874.

CASE C.

To all whom it may concern:

Be it known that I, HAYWARD A. HARVEY, of Orange, New Jersey, have invented certain Improvements in Composite Screws, of which the following is a specification:

My invention relates to cast-metal screws; and consists in the method of forming a screw having a shank of one kind of metal with a head of another kind cast upon it under pressure. My invention includes screws having wrought-metal shanks and cast-metal heads.

The drawing exhibits a perspective view of a wood-screw embodying my invention, a portion of the head being cut away to show the construction and the relation of the head to the shank.

The upper end of the shank *s* is dovetailed, as indicated by the notches *n* and *n'* on opposite sides of the shank. The head *h* is cast upon the dovetailed end of the shank, and

the nick is at the same time formed by pressure. The molten metal fills the notches, and in cooling shrinks tight upon the end of the shank, so that the head is firmly secured. The notches *n* and *n'* prevent the head from turning on the shank, and also hold the head down upon the end of the shank.

The head may be of bronze, silver, nickel, steel, or any other metal capable of being cast.

I claim as my invention—

The method described of forming heads on metal screws, which consists in forming the angular notched portion *n* and *n'* on the end of the shank, and casting the head upon and around such projecting portion, at the same time forming the nick, as set forth.

H. A. HARVEY.
